FIG. 4.

UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

STEREOTYPE-PLATE-CASTING-BOX-COOLING APPARATUS.

1,306,096.

Specification of Letters Patent. Patented June 10, 1919.

Application filed July 23, 1917. Serial No. 182,181.

To all whom it may concern:

Be it known that I, HENRY F. BECHMAN, a citizen of the United States, residing at Battle Creek, in the county of Calhoun and State of Michigan, have invented certain new and useful Improvements in Stereotype-Plate-Casting-Box-Cooling Apparatus; and I hereby declare that the following is a full, clear, and exact description thereof, reference being had to the accompanying drawings, which form part of this specification.

This invention is a novel improvement in means for cooling boxes for casting stereotype plates and the like, and is particularly intended for use in connection with the boxes of the type shown in my Patent No. 945,678, dated January 4, 1910, which boxes have a tiltable core that is subjected to great heat, as all the plates are cast around such core. It is the object of the present invention to keep the core or box at a sufficiently high temperature to prevent injury to the plates while being cast, and also to prevent the core or box becoming overheated and injured thereby.

The present invention is the result of a series of experiments I have made with such boxes in efforts to obtain the desired objects and by the present invention I have realized such object by simple and efficient means, and the plates can be cast very rapidly in such boxes without overheating the box, and without injuring the plates during the casting thereof.

The accompanying drawings illustrate diagrammatically one practical embodiment of the invention and the following description thereof, together with the drawings, will enable others skilled in the art to adopt and use the same; and in the claims the essential features of the invention for which protection is desired are summarized.

45 In said drawings:—

Figure 1 is a diagrammatical front elevation of a casting box and cooling apparatus connected therewith.

Fig. 2 is a top plan view of such box and apparatus. 50

Fig. 3 is an end elevation of Fig. 1.

Fig. 4 is a detail transverse section through the casting box.

The casting box may be of any suitable construction to cast plates of any desired kind, but I have illustrated a box for casting tubular stereotype plates, such box having a drag 1, cope 1^a and a core 1^b, substantially as described in my aforesaid patent. 55

The core 1^b is adapted to be inclosed between the cope and drag as indicated in Fig. 4, and in the annular space between the outer surface of the core and the inner surface of the cope and drag a tubular plate may be cast. 60

The core is preferably tiltably mounted on trunnions 1^d journaled in suitable bearings in the base frame 5, and after a plate is cast the drag may be opened and the core tilted, as indicated in dotted lines in Fig. 3, to enable the cast plate to be readily removed therefrom. 70

The core is hollow, and within the core are arranged two conduits or pipes 2 and 3 which respectively connect with passages 2^a and 3^a in the opposite trunnions 1^d. 75

Preferably the pipes 2 and 3 are parallel and of equal length and extend to, or near to, the top of the chamber in the core 1^b, so that the water or other fluid which is admitted into said core as hereinafter described will enter the core adjacent the top end or head thereof, which head is subjected to the greatest heat, as the metal is poured into the box at the head of the core. 80

Adjacent the casting box are two reservoirs or tanks 2^f and 3^f, which contain water or other suitable cooling fluid, and which tanks are preferably arranged at different levels, and may be supported by any convenient means (not shown). The water passage 2^a in the core is connected by suitable pipe connections 2^b, 2^c, and 2^d, with the lower end of tank 2^f. 90

The water passage 3^a is connected by suitable pipe connections 3^b, 3^c and 3^d with the tank 3^e.

The tanks 2^f and 3^f are provided with 5 water gages, g, g' respectively; and also with vent pipes 2^g and 3^g, respectively, at their upper ends.

The tanks may be supplied with water by means of pipes 4 and 4^a respectively 10 which may be provided with valves 4^b and 4^c, which are normally closed.

The proper fluid supply may be maintained in the tanks by observing the gages g, g'; the fluid being supplied through the 15 pipes 4, 4^a; and when the proper amount of fluid has been introduced into the tanks, valves 4^b, 4^c should be closed.

The tanks communicate freely with the atmosphere through the vent pipes 2^g, 3^g.

20 The tanks are filled with water or other suitable cooling fluid to about the level indicated by the dotted lines in Fig. 1, and of course the core and the pipe connections between the tanks and the core are also filled 25 with such fluid; and will be kept filled because the tanks are above the top of the core when the casting box is in closed position.

The core remains practically full of hot 30 fluid or water, and when the latter rises above a certain temperature or develops steam there will be a rush of fluid from the core back into one or the other of the tanks 2^f or 3^f, sometimes into both; and when any overheated fluid or steam is thus forced back 35 or out of the core, its place is immediately supplied by fluid from one or from both, of the tanks.

I have observed that the level of fluid in the tanks does not always remain uniform; 40 it will sometimes rise in the upper tank and then recede; and at the same time the fluid in the lower tank may recede when that in the upper tank rises. Sometimes the actions will be reversed. The fluid does not seem to have 45 any specific control over itself when confined in the hollow member of the casting box, and when heated it may pass back through either or both of the pipe connections to either or both of the tanks.

50 When using the type of box used in my said patent, the movement of fluid to and from the core is facilitated or assisted by the tilting movements of the core from the vertical position assumed for casting a plate, to 55 the horizontal, or substantially horizontal position, assumed for removal of a cast plate from the core.

I claim:

1. In apparatus for cooling stereotype 60 plate casting boxes and the like, a casting box, a pair of independent fluid reservoirs, and separate pipe connections between each reservoir and the interior of said casting box.

2. In apparatus for cooling stereotype 65 plate casting boxes and the like, a casting box having a hollow member, a pair of independent fluid reservoirs and separate pipe connections between said reservoirs and said hollow member. 70

3. Apparatus for casting stereotype plates, comprising a casting box having a hollow member, a pair of fluid conduits in said member, two independent fluid reservoirs, a pipe connection between one reservoir and one of the conduits in the hollow member, and an independent pipe connection between the other reservoir and the other conduit in said member. 75

4. In cooling apparatus for stereotype 80 plate casting boxes, the combination of a casting box having a hollow member, a pair of conduits in said member adapted to conduct fluid to the upper end thereof, a pair of tanks above the casting box, pipes connecting one tank with one of the conduits in the said member, and pipes connecting the other tank with the other conduit in said member. 85

5. Apparatus for casting stereotype 90 plates comprising a casting box having a hollow member, a pair of conduits in said member, two independent water tanks located adjacent and above the casting box, a pipe connection between one tank and one 95 of the conduits in the member, and an independent pipe connection between the other tank and the other conduit in said member.

6. In apparatus for cooling stereotype 100 plate casting boxes and the like, the combination of a casting box having a hollow tiltable core provided with interior pipes, a pair of independent tanks mounted at different levels, and separate pipe connections leading from the said tanks to the pipes in 105 said hollow core.

7. In cooling apparatus for stereotype 110 plate casting boxes and the like, the combination of a casting box having a hollow member, two independent fluid reservoirs arranged above the casting box and independent pipe connections between each reservoir and the hollow member. 115

8. In cooling apparatus for stereotype 120 plate casting boxes and the like, the combination of a casting box having a hollow member, two independent fluid reservoirs arranged at different heights above the casting box and independent pipe connections between each reservoir and the hollow member. 125

9. In cooling apparatus for stereotype plate casting boxes, the combination of a casting box having a hollow tiltable member, a pair of pipes in said member adapted to conduct fluid to the upper end thereof, a pair of tanks at different heights above the casting boxes, pipes connecting one tank

with one of the pipes in said member, and pipes connecting the other tank with the other pipe in said member.

10. Apparatus for casting stereotype plates comprising a casting box having a hollow tiltable core, a pair of pipes in said core, two independent water tanks located adjacent and above the casting box and at

different levels, a pipe connection between the lower end of one tank and one of the 10 pipes in the core, and an independent pipe connection between the other tank and the other pipe in said core.

In testimony that I claim the foregoing as my own, I affix my signature.

HENRY F. BECHMAN.
